[57] CLAIM

The ornamental design for a shoe sole, as shown and described.

DESCRIPTION

FIG. 1 is a bottom perspective view of a shoe sole showing my new design;

FIG. 2 is a left side elevational view thereof;

FIG. 3 is a right side elevational view thereof;

FIG. 4 is a front elevational view thereof;

FIG. 5 is a top plan view thereof;

FIG. 6 is a bottom plan view thereof;

FIG. 7 is a rear elevational view thereof;

FIG. 8 is bottom perspective view thereof as used in a shoe;

FIG. 9 is a left side elevational view of FIG. 8;

FIG. 10 is a right side elevational view of FIG. 8;

FIG. 11 is a front elevational view of FIG. 8;

FIG. 12 is a top plan view of FIG. 8;

FIG. 13 is a bottom plan view of FIG. 8; and,

FIG. 14 is a rear elevational view of FIG. 8.

The subject matter shown in broken line represents unclaimed environmental structure which is shown for illustrative purposes and forms no part of the claimed design.
